WITNESS:

H. A. La Clair

ATTORNEY

UNITED STATES PATENT OFFICE.

LOUIS ANDREW SOLLEDER, OF BEAUMONT, TEXAS.

GAME CARRIER.

Application filed December 8, 1922. Serial No. 605,709.

To all whom it may concern:

Be it known that I, LOUIS A. SOLLEDER, a citizen of the United States, residing at Beaumont, in the county of Jefferson and 5 State of Texas, have invented new and useful Improvements in Game Carriers, of which the following is a specification.

An object of this invention is to produce a device primarily designed for hunters' use 10 whereby game will be supported and carried without necessitating the employment of the usual game bags or the employment of the game pockets in the hunters' coat.

A further object is to produce a game 15 holder having a body portion constructed of spring wire centrally rounded upon itself to form arms which are extended at outward angles with respect to each other, said arms, adjacent the ends thereof being 20 bent outwardly in U-shape form and from thence merging into an arch to which the supporting strap is attached, one of the U-shaped members having hingedly connected thereto a lock bar, the opposite end 25 of the bar being hooked to engage the second U-shaped members, whereby the arms of the improvement will be compressed, and the heads of game, arranged therebetween effectively sustained upon the device.

30 The drawing, which accompanies and forms part of this application, illustrates a satisfactory embodiment of the improvement reduced to practice, and wherein:—

Figure 1 is a perspective view of the improvement, two of the carriers being connected together by a strap that is designed 35 to be supported from the shoulder of the hunter.

Figure 2 is a plan view of one of the 40 holders.

Figure 3 is a sectional view on the line 3—3 of Figure 2.

By reference to the accompanying drawing, it will be seen that preferably I employ 45 two holders which are connected together by a strap 1, the said strap designed to be arranged over the shoulder of a hunter or others conveying shot game. Each of the holders or carriers is of a similar construc-

tion, and therefore a description of one will 50 be taken as equally applicable to the other.

Each holder or carrier is formed from a single strand of spring wire of desired gauge. Each holder is centrally rounded upon itself, as at 2 and extended to provide 55 arms 3. The arms 3 are extended at outward angles with respect to each other and each of the said arms terminates in outwardly extended substantially U-shaped 60 portions 4. The portions 4 merge into an arch 5. The ends of the strand are arranged in this arch, and are soldered or otherwise connected. Hingedly secured in one of the U-shaped extensions 4 there is a locking bar 6, the opposite end of the said bar having a hook 7 to engage with the opposite U-shaped 65 member 4. Before the hook can be brought to engage with the said U-shaped member, it is necessary to compress the arms 3, as when the lock is released, the arms are 70 spread away from each other so that the heads of birds or other shot game may be disposed between the said arms and when the arms are compressed toward each other, the game is effectively supported on the 75 holder or carrier.

It is thought that the foregoing description, when taken in connection with the drawing will fully set forth the construction and advantages of the improvement to 80 those skilled in the art to which this invention relates, so that further detailed description will not be required.

Having described the invention, I claim:—

A game carrier constructed from a strand 85 of spring wire which is centrally rounded and extended to provide outwardly inclined arms, said arms having their ends formed with opposed outwardly directed U-shaped portions, and said U-shaped portions terminating in an arch, a locking bar hingedly secured to one of the U-shaped portions and having a hooked end to engage with the opposite U-shaped portion when pressure is exerted upon the arms of the holder to 90 force the same toward each other.

In testimony whereof I affix my signature.

LOUIS ANDREW SOLLEDER.
